UNITED STATES PATENT OFFICE.

OTIS M. FOWLER, OF INDIANAPOLIS, INDIANA, ASSIGNOR, BY MESNE ASSIGNMENTS,
TO C. FEED YEGGE, TRUSTEE, OF EVANSTON, ILLINOIS.

WIRE-BOUND BOX.

1,284,639.

Specification of Letters Patent. Patented Nov. 12, 1918.

Application filed November 4, 1915. Serial No. 59,529.

To all whom it may concern:

Be it known that I, OTIS M. FOWLER, a citizen of the United States, residing at Indianapolis, in the county of Marion and State of Indiana, have invented a new and useful Wire-Bound Box, of which the following is a specification.

The object of my invention is to produce a wirebound box of such form that the 10 cleats, forming part thereof, will thoroughly protect the ends of the sheet sections; and extend from edge to edge of each sheet; and interlock to prevent lateral slipping of the sheet sections, the construction being such 15 that the cleats may be formed at no greater expense than the cleats now commonly in use.

The accompanying drawings illustrate my invention. Figure 1 is a perspective view of 20 a completed box embodying my invention; Fig. 2 a plan of a box blank embodying my invention, one end of each sheet section being removed to show the sheet faces of one series of cleats; Fig. 3 a perspective view of one cleat, with a fragmentary portion of a sheet attached thereto, and an adjacent cleat end; Fig. 4 a perspective view of the associated ends of two cleats; Fig. 5 a perspective view of adjacent ends of two 25 cleats, in a slightly modified form.

In the drawings, 10 indicates the main body of a cleat provided at one end with a tenon 11 which is conveniently formed at the middle of the cleat by equal cross rabbits 12 and 13. Along the sheet face of the cleat I form a longitudinal rabbet 14 at the inner corner of the cleat. At the opposite end, the cleat is cross-rabbeted at 16 so as to form a tongue 17 lying in the plane of 30 the portion 18 of the cleat, which forms the shoulder of the rabbet 14. The cross rabbet 16 is preferably formed by an ordinary mortising cutter which will serve to produce a shallow mortise 19 and a short leg 21 parallel with the tongue 17 and spaced from said tongue by the shallow mortise 19.

The rabbet 14 has a depth equal to the thickness of the sheet material 22, and the sheets 22 have widths equal to the total 35 lengths of the cleats to which they are attached, i. e., from the tip of tenon 11 to the tip of tongue 17. The sheets 22 are laid in the mortises 14, the cleats being made rights

and lefts, as shown in Fig. 2, and secured in place in the usual manner by means of staples 23 straddling binding wires 24 and passing through the sheets 22 into the cleats 10.

When the parts are folded into box form, as shown in Fig. 1, that edge of each sheet which lies flush with the ends of the tenon 40 11, will be overlapped by the inner face of the sheet of the adjacent section which has its edge flush with the ends of tongues 17. The tenons 11, at their edges farthest from the sheet, take into the mortises 19 of the 45 adjacent cleats so as to laterally interlock the cleats when in folded position. The several portions 18 of a series of cleats completely overlap all of the end edges of the sheet sections, as clearly shown in Fig. 1, 50 and thus protect the sheets from absorption of moisture when the box is set endwise upon a wet surface.

In the form shown in Fig. 5, each cleat 10' is provided upon its sheet surface with a 55 longitudinal rabbet 14. At one end each cleat is provided with a cross rabbet 25 at the outer face of the cleat, and at the other end with a cross rabbet 26 at the inner face of the cleat, the tongue 27, formed by rabbet 25, having a length equal to the width of the shoulder 28 formed by the cross rabbet 26, while the tongue 29, formed by the cross rabbet 26', has a length equal to the 60 width of tongue 27 plus the thickness of the sheet material (i. e., the depth of rabbet 14) and a width equal to the entire thickness of the cleat. In this form of cleat, as 65 in the form shown in the other figures, the sheet material will have a width equal to the full distance between the end of tongue 27 and the end of tongue 29, and when the sections of the box are folded together, the 70 sheets will overlap in precisely the same manner and the ends of the sheets will be 75 similarly protected.

In the commercial production of my improved cleats, a pair of cleats (right and left) will be formed by resawing and passing beneath a rotary cutter to form the rabbits 14. The cleats will then be passed through the usual mortising-and-tenoning machine, the cutters on one side of the machine being arranged to form the tenons 11 and at the other side of the machine being 80 arranged to produce the mortise 19 and short 85

leg 21. The production of my improved cleat, therefore, does not involve additional expense.

I claim as my invention:

- 5 1. A package blank comprising a plurality of sections, each section comprising a sheet member and a transverse cleat, said cleat having a longitudinal rabbet for the reception of the sheet, a tongue at one end in the plane of that portion of the cleat which forms the shoulder of the rabbet, and a short leg parallel with said tongue and spaced therefrom by a shallow mortise, and at the 10 other end a tongue in the plane of the mortise and having a width equal to that portion of the cleat beneath the attached sheet.
- 10 15 2. A package blank comprising a plurality

of sections, each section comprising a sheet member and a transverse cleat; said cleat having a longitudinal rabbet for the reception of the sheet, a tongue at one end in the plane of that portion of the cleat which forms the shoulder of the rabbet, and a short leg parallel with said tongue and spaced therefrom by a shallow mortise, and at the 20 other end a tongue in the plane of the mortise and having a width equal to that portion of the cleat beneath the attached sheet.

In witness whereof, I have hereunto set my hand at Indianapolis, Indiana, this second day of November, A. D. one thousand nine hundred and fifteen.

OTIS M. FOWLER.
